(57) CLAIM

The ornamental design for a mattress, as shown and described.

DESCRIPTION

FIG. 1 is a top, front and left side perspective view of a mattress, showing my new design;

FIG. 2 is a top plan view thereof;

FIG. 3 is a left side perspective view thereof; and,

FIG. 4 is a front side perspective view thereof.

The bottom, right, and rear side view are omitted because they are identical with the top, left and front view, respectively.
